TUBE MAKING MACHINE

John L. Ferguson, Joliet, Ill., assignor, by mesne assignments, to Paul Hawkins, Los Angeles, Calif.

Application November 9, 1934, Serial No. 752,210

11 Claims. (Cl. 93—80)

This invention relates to tube making machines and more particularly to automatic machines for manufacturing so-called "spiral wound tubes" of any desired predetermined length.

5 The particular embodiment illustrated and described herein is arranged to continuously wind an automatically progressing tube on an angularly adjustable non-rotatable mandrel. Automatic means is provided whereby the continuously progressing tube may be cut into sections of predetermined length. The tubes are preferably formed of comparatively narrow strips of tape, usually paper, which are automatically spirally wound on the mandrel to form the continuously progressing 10 tube. A plurality of tapes may be continuously wound on the mandrel to form a desired type of tube.

20 The present invention provides an automatic tube winding machine in which the tape or tapes may be fed to the mandrel from a fixed position and in which the mandrel may be angularly adjusted to cause any desired width of tape to be wound thereon with all of the turns in uniform predetermined relation. Means is also provided 25 whereby the relation of the turns may be varied at the will of the operator and without stopping the machine. The position of the mandrel relative to any predetermined width of tape or tapes may be so adjusted that the turns may be snugly 30 adjacent or may be overlapped or may be spaced in any desired manner.

35 It is an object to provide a tube winding machine in which the position of the tape fed thereto is fixed and in which an angular adjustment of the mandrel relative to the tape provides accurate means for determining the relation of the coils in the finished tube.

Another object is the provision of automatic 40 cut-off means, whereby the continuously progressing tube may be accurately cut into sections of predetermined length, regardless of the type of winding or of the winding speed or of the rate at which the tube is progressed from the mandrel.

A further object is the provision of a tube winding 45 machine having a non-rotatable mandrel in which suitable means is provided for rotating the tube on the mandrel to wind the tape thereon to simultaneously form the tube and to continuously progress the tube from the mandrel.

50 A tube winding machine is provided having a mandrel angularly adjustable relative to the tape being wound thereon and in which a single means is provided for winding the tube on the mandrel and simultaneously progressing the tube thereon.

55 A further object is the provision of a tube wind-

ing machine having a fixed mandrel and a constantly driven pressure device cooperating with the mandrel to wind the tape thereon to form a continuous tube, and wherein the mandrel and pressure device is so related as to cause the tape 5 to feed on the mandrel in a substantially unvarying relation thereto and to simultaneously and continuously feed the wound tube longitudinally of the mandrel.

The invention also provides a variable speed 10 winding mechanism whereby the speed of winding and the consequent progression of the tube may be varied, in combination with an automatic cut-off means for cutting the tube into sections 15 irrespective of the speed of winding and rate of progression.

A further object is the provision of a tube winding machine in which the tubes may be rapidly and conveniently wound and cut into sections and in which a minimum number of adjustments will 20 provide a maximum number of tube variations.

In the manufacture of spiral wound tubes it is desirable that one or more of the tapes be provided with a dry adhesive previously applied thereto and moistened as the tape is fed to the 25 mandrel, or a suitable moist adhesive may be applied during the winding operation. Also, it is sometimes desirable to apply a lubricant, or impregnating material, or a coating similar to paraffin to the tape whereby the tube may be made 30 substantially moisture proof. It is therefore an object to provide suitable means for accomplishing these desirable results and whereby substantially any desired type of adhesive or coating or impregnating material may be used or applied during 35 the winding operation.

Further objects will be apparent from the specification and the appended claims.

In the drawings:

Figure 1 is a side elevation of one embodiment 40 of the invention, a portion being broken away for purposes of illustration. In this view, as well as in Fig. 2, the mandrel and cooperating pressure roller are illustrated in parallel axial relation, also for purposes of illustration.

Figure 2 is a front elevation of the embodiment 45 illustrated in Fig. 1, with a portion of the mandrel carriage broken away for convenience in illustration.

Figure 3 is a top view of the embodiment illustrated in Figs. 1 and 2 but with the mandrel moved to operative angular position relative to the pressure roller and the tape to be wound on the mandrel.

Figure 4 is a horizontal axial section through 55

the mandrel and tube cutting mechanism supported therein.

Figure 5 is an enlarged fragmentary sectional view of the tube cutting end of the mandrel as illustrated in Fig. 4.

Figure 6 is a fragmentary end view of the mandrel as illustrated in Fig. 5 with the cutter-guide retaining plug removed.

Figure 7 is a fragmentary top view of the end 10 of the mandrel as illustrated in Fig. 6.

Figure 8 is a diagrammatic top view of the mandrel and pressure roller and a plurality of tape being wound thereon to form a continuously progressing tube.

15 Figure 9 is an axial section through the cutting end of the mandrel and illustrates a modified form of cutting mechanism.

20 Figure 10 is a transverse detail section of the modified form of the cutting device and taken on a line corresponding to line 10-10 of Fig. 9.

Figure 11 is a longitudinal section through the tape guiding means and illustrates a method of water-proofing or impregnating or lubricating the inner tape of a double wound tube.

25 Figure 12 is a transverse section through the fixed tape guide and taken on a line corresponding substantially to line 12-12 of Fig. 11.

30 Referring to the drawings in detail, the embodiment illustrated comprises a supporting frame 1 having transverse cross bars or frame members 2 and 2a in which a vertical shaft 3 may be rotatably supported. A horizontal mandrel 4 is mounted on a mandrel carriage 5 and this carriage is pivoted on the shaft 3 by means 35 of suitable bearings 6 and 7. The vertical axis of the shaft 3 preferably intersects the horizontal axis of the mandrel 4 and, therefore, the mandrel 4 may be angularly adjusted in a horizontal plane by lateral swinging movement of the carriage 5 on the vertical axis of the shaft 3. The mandrel 4 is preferably non-rotatable and is fixedly secured in a post 8 on the carriage. The carriage 5 may be adjusted to angularly position the mandrel, by means of a hand wheel 9 on a threaded 40 shaft 10. This shaft is rotatably anchored in a bearing pivoted at 11 on the frame 1 and is threaded through a pivoted block 12 secured to the carriage 5. By this arrangement the angular position of the mandrel 4 may be accurately 45 adjusted as desired by manipulation of the hand wheel 9.

50 A pressure roller 13, preferably of soft rubber, is positioned above the mandrel in a position to frictionally engage tape between the roller and mandrel and to wind the tape spirally thereon when the mandrel is in an adjusted angular position corresponding to the width of the tape and the type of tube desired. The roller 13 is preferably located directly over the axis of the vertical shaft 3 and therefore on the vertical pivotal axis of the mandrel and carriage. The roller 13 is secured to a shaft 14 mounted in an adjustable bearing member 15, which latter is, in turn, pivoted at 16 on a bracket 17 secured to the frame 1. The bearing member 15 is provided with an outwardly extending worm gear segment 18 meshing with a worm 19 (Figures 2 and 3). A hand wheel 20 on the shaft of the worm 19 permits the pressure of the roller 13 against the mandrel 70 to be accurately adjusted and also permits the pressure roller to be raised to permit the insertion of tape on the mandrel and between the mandrel and the roller.

75 The pressure roller 13 is constantly driven from a suitable power source, such as a motor 21

mounted on the frame 1, and connected to drive the pressure roller shaft 14 and pressure roller thereon through a suitable transmission, including a variable speed mechanism. The transmission from the motor 21 comprises a belt 22 driving a pulley 23 secured to a rotatable shaft 24. The shaft 24 is mounted in suitable bearings on a bracket 25 secured to the frame 1. An adjustable member 26 is pivotally mounted on the axis of the shaft 24 and is provided at its opposite end 10 with a variable speed pulley 27 on a shaft 28, which latter is mounted in suitable bearings in the adjustable member 26. The shaft 28 and the variable speed pulley 27 thereon are driven from the shaft 24 by means of a sprocket chain 29 on 15 suitable sprockets secured to the shaft 24 and shaft 28, respectively. The variable speed pulley 27 is connected in driving relation with a pulley 30 by means of a belt 31. The pulley 30 is secured to a short shaft 32, which latter is mounted 20 in a suitable bearing on the bracket 17 at the top of the machine. A pinion 33 is secured to the other end of the shaft 32 and is in mesh with a gear 34 secured to the pressure roller shaft 14. The pressure roller may, therefore, be 25 constantly driven from the motor 21 by means of this transmission.

The variable speed pulley 27 forming a part of this transmission is of the ordinary type in common use, which usually comprises two cone-faced discs arranged to receive a V-shaped belt 31 therebetween. As the structure and operation of such a variable speed pulley is old and well known they require no further description.

30 The bracket 25 is provided with an arm 35 overhanging the adjustable member 26, and a screw 36 is arranged for adjustable engagement with the member 25, whereby the distance between the pulleys may be varied by moving the pulley 27 a greater or lesser distance from the pulley 30 to obtain a desired speed of the pressure roller 13.

35 It will be particularly noted that a desired angular position of the mandrel 4 may be obtained by manipulation of the hand wheel 9; a suitable pressure of the roller 13 may be obtained by adjusting the hand wheel 20; and the speed of the roller 13 may be accurately adjusted by means of the adjusting screw 36, thereby providing a maximum number of tube variations with 50 a minimum number of adjustments.

40 As previously stated, the mandrel 4 in the embodiment illustrated does not rotate but is fixed in the support 8 on the mandrel carriage 5, and suitable tape may be wound on the mandrel in 55 the manner illustrated in Fig. 8 by means of the pressure roller 13. It will be understood that one or more tape may be simultaneously wound on the mandrel to provide the desired type of tube; also, that the angular relation of the pressure roller and mandrel and the frictional engagement of the tape therebetween will cause the finished tube to be rotated on the mandrel to continuously wind tape thereon and to simultaneously progress the tube longitudinally on the 65 mandrel and beyond the free end thereof. Therefore, the speed of the pressure roller 13 determines the speed of winding and the consequent longitudinal progression rate of the tube from 70 the mandrel.

75 In the embodiment illustrated, particularly as shown in Figs. 2 and 8, tapes A and B are simultaneously wound on the mandrel to provide a continuously progressing tube comprising an inner layer of the spirally wound tape A and an 75

outer layer of the similarly wound tape B. In the winding illustrated, the tape B overlaps substantially one-half of the tape A and, therefore, completely covers the joint between the edges of the turns of the tape A. The tapes A and B may be of the same width or may be of different widths, in accordance with the type of tube desired.

In operating the machine, the mandrel is adjusted to a desired angle C (Fig. 8), which angle 10 determines the lead of the winding, and the mandrel may be accurately adjusted so that all of the turns of the tape as they are wound on the mandrel will be closely adjacent if desired. A further adjustment of the mandrel in one direction 15 will cause the tape to wind on the mandrel with overlapping turns, while an adjustment in the opposite direction will cause the turns to be spaced any desired amount.

The sine of angle C for closely adjacent turns 20 may be found by dividing the width of the tape by the circumference of the mandrel. It will, therefore, be obvious that a protractor may be laid out on either the mandrel carriage or the frame and a pointer on the cooperating member 25 and the required angle for any width of tape for closely wound tubes may be easily determined. Also, any desired width of tape may be used to provide any desired type of winding, and it is only necessary to angularly adjust the mandrel by 30 means of the hand wheel 9 in order to adjust the winding of the tape as desired. This may be done while the machine is in operation and without previously determining the angle. The tape is preferably fed to the mandrel through a suitable fixed guide and a plurality of tape may be applied simultaneously as shown.

The roller 13 is preferably so positioned relative to the tape being fed to the mandrel that the pressure is applied after the first complete turn 40 of the tape on the mandrel, as illustrated in Fig. 8. The angular relation of the pressure roller causes the wound tape and the tube formed thereby to be rotated on the mandrel and, simultaneously, the tube will be longitudinally progressed beyond 45 the end of the mandrel. The tube is therefore constantly moving longitudinally from the mandrel and may be automatically cut into sections on a line corresponding to line D (Fig. 8) by means of suitable cutting mechanism which is 50 mounted within the fixed shell of the mandrel.

The cutting mechanism is illustrated in Figs. 4 to 7, inclusive, and comprises a sleeve 37 mounted for longitudinal movement in the mandrel 4. This sleeve is provided with a stop portion 38 55 and is normally retained in the position illustrated in Fig. 4 by means of a spring 39. A rotatable hollow shaft 40 is mounted in the sleeve 37 and provided with a pulley 41 secured thereto by which it may be constantly driven at a high speed 60 from a suitable power source.

The rotatable shaft 40 is provided at its outer end with a head 42. This head 42 is bored out in a manner to provide an inner curved surface 43 and is also provided with a plurality of longitudinal slots 44 arranged to receive the radial arms 45 of a cooperating slotted cutter guide member 46, which latter is provided with a cone-like guide surface 47 spaced from the guide surface 43 in order to allow suitable cutting members to be guided therebetween. A retaining plug 48 is threaded into the slotted end of the head to retain the guide member 46 therein in the position illustrated in Figs. 4 and 5.

A longitudinally movable rod 49 is mounted in 75 the hollow shaft 40 and a plurality of radially

positioned cutters, comprising wires 50, are secured to this rod by means of a bushing 51 and a cooperating tapered clamping screw 52, which latter is threaded into the end of the longitudinally movable rod 49 in a manner to clamp all of 5 the cutting wires 50 in angular radial position therein. The cutting members 50 may be of any suitable material, but in the present instance are formed of flexible steel wire such as so-called "piano wire". The free ends of these wires are 10 guided outwardly by means of the cooperating guide surfaces on the member 46 and the head 42. The outer ends of these wires are sharpened and it will be obvious that when the rod 49 is longitudinally moved, the outer sharpened ends of all 15 of these wires will simultaneously move outwardly into cutting relation with any tube which may be on the mandrel 4.

The longitudinally movable cutter rod 49 is provided at its opposite end with a collar 53 and 20 is normally retained with the cutters retracted, and in the position shown, by means of a spring 54. The rod 49 may be longitudinally moved to move the cutters to cutting position by means of 25 a cam controlled arm 55 which is suitably operated by mechanism which will be described later.

The longitudinally movable sleeve 37, in which the cutter shaft 40 is mounted, may also be moved longitudinally by means of a suitable cam arm 56, the yoke of which is illustrated in Fig. 4 in 30 connection with a suitable slot and pin connection to the sleeve 37, whereby the sleeve may be moved longitudinally when the cam arm 56 is operated in a manner to be described later. It will therefore be apparent that if the sleeve 37 is moved 35 longitudinally to the right (Figs. 4 and 5) the entire head 42, including the cutters 50 therein, will also be moved and in this movement may be in timed relation to the continuously progressing movement of the tube on the mandrel. Therefore, if during this longitudinal movement of the cutter head 42 the cam controlled arm 55 is 40 operated to move the cutter rod 49 longitudinally in the same direction and relative to the head 42, the cutters will all be simultaneously moved 45 outwardly into the path of the tube, and due to the large number of cutters and the high speed at which the cutter head is driven the tube will be almost instantly cut and the cutters may then be immediately retracted and the cutter head 42 50 returned to its normal position by rearward movement of the sleeve 37.

It should be particularly noted that any variation in the speed of the pressure roller 13, previously described, will cause a corresponding increase in the tube winding and longitudinal progressing rate of the tube from the mandrel. Therefore varying the speed of the roller will also vary the length of the sections cut from the tube, and the length may be very accurately determined. 60

It is desirable, although not necessary, that the longitudinal movement of the cutter head should be substantially the same as the rate of longitudinal movement of the tube. In fact, the sections 65 may be satisfactorily cut from the tube without any longitudinal movement of the cutter head as the large number of cutters are so close together and each one cuts so short a distance that the tube is almost instantaneously severed and the 70 cutters withdrawn.

The pulley 41, secured to the cutter shaft 40, is driven from a motor 57 by means of a belt 58. The motor 57 is secured to the mandrel carriage 5 and is movable therewith. The longitudinal 75

movement of the sleeve 37 and the cutter shaft 49 is controlled by means of a cam 59 which is rotatably mounted on the vertical shaft 3. This cam comprises a portion 60 arranged for cooperation with a suitable roller on the cam arm 56 whereby at a predetermined time the sleeve 37 will be moved longitudinally in the direction of movement of the tube on the mandrel. The cam arm 56 is pivoted at 61 on the mandrel carriage 5. The 5 cam controlled arm 55, for causing the longitudinal movement of the cutter rod 49 to extend the cutters into cutting position, is secured to a vertical rock-shaft 62 on the carriage 5, and a cam arm 63 is also secured to the rock-shaft and provided with a roller for cooperation with a raised portion 64 on the cam 59, whereby the cutter may be momentarily expanded. The cam 59, for controlling these operations, is provided with a bearing sleeve 65, on the opposite end of which is secured a beveled gear 66. This gear is in mesh with a pinion 67 on a shaft 68 mounted in suitable bearings and provided with a gear 69 thereon meshing with a pinion 70 secured to the shaft 24 of the main transmission and between the motor 25 and the variable speed mechanism, the shaft 24, as previously stated, being driven directly from the motor by means of the belt 22. By this arrangement the cam speed is not affected by a change in the pressure roller speed and the length 30 of the cut sections may therefore be varied by changing the roller speed.

The machine is very flexible in operation and many different types of tubes may be wound thereon, and adjustments may be easily and accurately made to meet all necessary requirements.

In the present embodiment, the method of guiding and treating a plurality of tapes as they are fed to the mandrel is illustrated in Figs. 2 and 3, and, although the mandrel and the pressure 40 roller are illustrated in parallel relation in Fig. 2 for purposes of illustration, it will, of course, be obvious that an angular position relative to the tape as shown in Fig. 3 is necessary to provide a desired type of winding. As shown in Fig. 2, a 45 roll of tape 71 may be supported in any suitable location and the tape is guided over the roller 72 and passes under and in contact with a felt swab or other suitable material 73 which is supported on a bracket 74 on frame 2a, and the tape 50 then passes around a roller 75 and through a suitable guide block 76 to the mandrel 4. A tank 77 may be supported above the felt member 73 and provided with a tube or channel 78 whereby paraffin or a suitable water-proofing or lubricating or 55 impregnating material may be applied to the felt member 73, which in turn applies it to the inner surface of the inner tape A. The inner surface of the tube may therefore be completely coated with paraffin or other material if desired.

60 The outer tape B is preferably provided on its inner surface with a suitable adhesive. This may be a dry adhesive which has been previously applied to the tape and a moistener 79 may be used for moistening the adhesive whereby the coils will be caused to adhere by the pressure of the roller 13. The moistener 79 may, of course, be used either to apply moisture to a dry adhesive previously applied to the tape or to apply a moist adhesive to the tape, and comprises a moistener or adhesive-applying roller 80 partially submerged in either water or adhesive, the tape being guided over and under suitable rollers and in contact with the applying roller 80. A scraper 81 is also provided whereby the surplus of either moisture

or adhesive may be removed as the tape is fed through the device.

The guide block 76 is illustrated in detail in Figs. 11 and 12 and comprises a base 82 secured to the bracket 74 and provided with a longitudinal slot 83 to guide the inner tape A. An intermediate cover 84 is hinged at 85 and may be raised for the insertion of the tape. A second cover 86 is hinged on the intermediate cover at 87 and is provided with a guide slot 88 for the tape B, this 10 guide slot being off-set, as illustrated, so that the tapes may overlap in a desired manner. It will, of course, be understood that varying thicknesses and varying widths of tape may be used and may be made to overlap as desired, and a guide block 15 15 may be provided in accordance with a desired tape relation. For instance, the outer tape may be of considerably thinner material than the inner one and arranged to cover the joint between the turns of the inner coils and be cemented thereto. With 20 such a construction the tube may be easily unwound from around its contents by unwinding the inner turns and the outer thin turns will easily tear along the spiral joint of the inner tape. Such a construction is sometimes used for ice 25 cream containers.

The guide block 76 is provided with a latch 89 whereby the hinged covers may be retained in position. Figs. 9 and 10 illustrate a modified form 30 of cutter head in which the shaft 40a is provided with a flange 90 on which is pivoted a plurality of segmental knives 91. These knives are pivoted at 92 and are normally retained in non-cutting position by means of tapered pins 93 secured in a flange 94 on the end of a longitudinally movable 35 rod 49a, and snugly fitting through holes 95 in the knives. The pins 93 also extend into holes 96 in the flange 90. It will be obvious that when the rod 49a is longitudinally moved, the tapered pins 93 will be partially withdrawn from the holes 95 40 in the knives 91, and as the cutter head rotates at high speed relative to the tube, the centrifugal force will cause the knives to be forced outwardly as illustrated by dotted lines in Fig. 10, thereby quickly cutting the tube. The cutter head preferably rotates in the direction of the arrow in Fig. 10, and the forward edges 97 of the knives are sharpened so that the cutting is accomplished by the points of the knives.

It will also be apparent that when the rod 49a 50 is returned to its normal position, the tapered pins 93 will simultaneously retract all of the knives to the non-cutting position shown in full lines in Fig. 10.

Modifications may be made in the embodiment 55 herein shown and described without departing from the spirit of the invention, and it is desired, therefore, that the invention be limited only by the prior art and the scope of the appended claims.

Having thus disclosed this invention, what is claimed and desired to be secured by Letters Patent is:

1. A tube winding machine comprising a mandrel, a rotatable pressure roller arranged to wind a tape spirally on said mandrel, the axis of the pressure roller being at an angle to the mandrel axis substantially equal to the lead of the spiral, and means for changing the relative angle between said mandrel and said pressure roller while maintaining the angular relation between the roller and tape.
2. A tube winding machine of the character described comprising a mandrel, and a pressure roller cooperating with said mandrel to wind

tape thereon to form a tube, said mandrel being pivoted for angular adjustment relative to said roller on an axis intersecting the axes of said mandrel and said roller.

5. In a tube winding machine, a carriage, a mandrel supported by said carriage, means for pivoting said carriage for swinging movements, means for moving said carriage on its pivot, and a rotatable pressure roll cooperating with said mandrel.

6. In a tube forming machine, a pivotally supported carriage, a mandrel carried by said carriage, means for adjusting said carriage, a vertically tiltable frame above said carriage, a roller journaled in said frame and means for tilting said frame.

7. In a tube forming machine, a vertical shaft, a carriage pivoted on said shaft, a mandrel supported on said carriage, means for adjusting said carriage in azimuth, and a roller cooperating with said mandrel, said roller being in vertical alignment with said shaft.

8. In a tube forming machine, a carriage, means for supporting said carriage for horizontal adjustment including a pivot member, a mandrel supported by said carriage, a pressure roller cooperating with said mandrel in the axis of said pivot member.

9. In a tube forming machine, a mandrel, a pivotal support for said mandrel, means for adjusting said mandrel on said support, and a roller cooperating with said mandrel in the axis of said pivotal support.

10. In a tube forming machine, a vertical pivot member, a carriage having bearings journaled upon said pivot member, means for swinging said carriage on said pivot member, a mandrel supported upon said carriage, and a vertically adjustable roller cooperating with said mandrel in the axis of said pivot member.

11. A tube winding machine including a man-

drel, a pressure roller cooperating with said mandrel to wind tape thereon to form a tube, means mounting said pressure roller for rotation relative to said mandrel about an axis extending at an acute angle to the longitudinal axis of said mandrel, and means pivotally mounting said mandrel relative to the axis of said roller, the axis of said pivot being disposed in a line passing through both the longitudinal axis of said mandrel and the axis of rotation of said roller along 10 a plane extending at right angles to the axis of said roller and within the boundaries of said roller.

12. A tube winding machine including a mandrel, a pressure roller cooperating with said mandrel to wind tape thereon to form a tube, means mounting said pressure roller for rotation relative to said mandrel about an axis extending at an acute angle to the longitudinal axis of said mandrel, and means mounting said mandrel for 20 movement relative to said roller to vary said angle, the axis of said movement passing through the intersection of two given planes one drawn through the mandrel at right angles to its longitudinal axis and the other drawn through the 25 roller at right angles to its axis of rotation.

13. A tube winding machine including a mandrel, a pressure roller cooperating with said mandrel to wind tape thereon to form a tube, means mounting said pressure roller for rotation relative to said mandrel about an axis extending at an acute angle to the longitudinal axis of said mandrel, and means mounting said mandrel for movement relative to said roller to vary said angle, the axis of said movement passing through the intersection of two given planes, one drawn through the mandrel at right angles to its longitudinal axis and the other drawn through the roller at right angles to its axis of rotation and passing through the center of the face of said roller. 40

JOHN L. FERGUSON.
